UNITED STATES PATENT OFFICE.

GEORGE W. HANNA AND EMIL STERZING, OF HARTFORD, CONNECTICUT.

DESIGN FOR A PATTERN FOR VEHICLE-TIRES.

SPECIFICATION forming part of Design No. 28,335, dated March 1, 1898.

Application filed June 8, 1897. Serial No. 639,924. Term of patent 7 years.

To all whom it may concern:

Be it known that we, GEORGE W. HANNA and EMIL STERZING, citizens of the United States, and residents of Hartford, in the county of Hartford and State of Connecticut, have invented a certain new and useful Design for a Pattern for the Tread or Wearing Surface of a Vehicle-Tire, of which the following is a specification.

- 10 Figure 1 represents in plan a portion of a vehicle-tire to which our pattern of tread-surface is applied. Fig. 2 is a transverse section of such tire, showing the altitude of the parts constituting the pattern.
- 15 This pattern of tread consists of a series of raised zigzag ribs A, placed in parallelism to one another and having globular enlarge-

ments at the angles, as shown at B. The drawings show two of these zigzag ribs associated together in parallelism and on either 20 side of the central line of a vehicle-tire.

We claim—

The design for a pattern for the tread or wearing surface of vehicle-tires, substantially as shown and described. 25

Signed at Hartford, in the county of Hartford and State of Connecticut, this 27th day of March, A. D. 1897.

GEO. W. HANNA.
EMIL STERZING.
